[57] **CLAIM**

The ornamental design for an inlaid combination calculator and card holder, as shown and described.

DESCRIPTION

FIG. 1 is a front perspective view of an inlaid combination calculator and card holder of my new design in the open position;

FIG. 2 is a top plan view thereof;

FIG. 3 is a front elevation view thereof in the open position;

FIG. 4 is a side elevation view of FIG. 3;

FIG. 5 is a rear elevation view thereof in the open position;

FIG. 6 is a bottom plan view thereof; and,

FIG. 7 is a perspective view thereof in the closed position. The broken line depictions of the keypad in FIGS. 1 and 3 have been shown for illustrative purposes only and form no part of the claimed design.
